UNITED STATES PATENT OFFICE.

FRANK E. LOWENSTEIN, OF ATLANTA, GEORGIA.

CONTAINER.

Application filed June 30, 1925. Serial No. 40,693.

To all whom it may concern:

Be it known that I, FRANK E. LOWENSTEIN, a citizen of the United States of America, residing at Atlanta, in the county 5 of Fulton and State of Georgia, have invented certain new and useful Improvements in Containers, of which the following is a specification.

This invention is directed to a convertible container, which following its primary 10 use, may be readily and conveniently adapted for a secondary use. More specifically, the construction provides a candy or like container, adapted in its original package condition to be sealed in an air tight manner through the medium of a friction top plug or closure, the latter being formed so that following the removal of the candy or other material from the container, 15 the plug may be again pressed into closing position and serve as a toy savings bank.

The invention is particularly concerned 20 with the formation of the plug, which aside from its usual structure as a friction sealing plug, is constructed in its bottom with a narrow slot outline formed by dividing the material on three sides of such slot outline and perforating or scoring it on the fourth side. The bottom or under side of the plug 25 throughout and beyond the slot outline area is provided with a label or other readily frangible material adhesively secured in place and serving to close and effectively seal the incisions or perforations in the top 30 which define the slot outline. Thus the plug for effective purposes when the original or other material is contained in the container acts as a complete sealing air tight closure, and following the removal of the material 35 from the container, the plug material within the formed slot outline may be readily displaced and the frangible seal broken through or removed, so that a coin slot is formed in the top plug serving when the latter is re- 40 placed in the container to provide a convenient simple toy savings bank.

The invention is illustrated in the accompanying drawings, in which:

Fig. 1 is a perspective view of a container 50 with the improved top plug in position.

Fig. 2 is an enlarged plan view of the friction top plug, viewed from the upper side.

Fig. 3 is a similar view taken from the 55 lower side.

Fig. 4 is a sectional view of the top plug

with the material within the slot outline turned back to permit the use of the top plug with the container to provide a toy savings bank.

The invention as shown comprises a container 1, which may be constructed in any desired shape and size, and while preferably of metal, any appropriate material may be used. The container in the present specific embodiment is designed to receive candy or the like, which from its nature requires an air tight sealing after packing and until delivered to the customer. For this purpose, the top of the container is formed with the 70 usual opening 2, which receives a closure 3, in the form of a friction top plug, the detailed construction and arrangement of which is well understood in the art. The sealing is effected by forcing the plug into 75 position, which incident to its wedging co-operation with the wall of the opening in the container insures an effective sealing at the edges of said opening.

For the purposes of the present invention, 80 this plug is formed in its bottom wall with the outline of a coin slot. This is indicated as a narrow elongated slot 4 outlined by cutting the material of the bottom of the friction top entirely through such material on one longitudinal edge as 5 and the end edges as 6. Throughout the remaining longitudinal edge 7, the material is simply perforated or scored to avoid entirely separating the slot closure from the friction 85 top plug. In the use of the top plug as a closure for the container as an original package, the opening formed in the bottom of the top plug by the slot formation described is sealed by the application of wa- 90 ter-proof material to the bottom surface of the top plug, or as indicated in the drawings, by the application of a label or other adhesive closure to such top plug bottom. Thus for all effective sealing purposes, the 95 bottom of the top plug is unbroken, and when applied to the container in its original or subsequent use as a candy or material container, the contents will be effectively sealed by the plug. When the container 100 is no longer desired for use as such, the sealing label or material may be removed or broken through, and the material of the plug bottom within the defined outline 105 turned back on the perforated edge 7, thereby defining a coin slot in the top plug, which following the forcing of said plug to its

110

seat in the container in the usual manner permits said container to serve as a toy savings bank.

The invention is primarily designed to provide a means for the continued use of containers, particularly for candy, after the candy has been exhausted, and to permit this additional use through a simple and inexpensive expedient as described. Thus the container from which the candy or other material has been exhausted may be readily and conveniently converted by any one to serve as a toy savings bank for the convenient reception of coins or the like. It is understood of course that the slot formed in the friction top plug will preferably be of a size to receive the largest coin ordinarily used.

It will of course be appreciated that the movable tongue may be formed in the bottom of the container rather than in the plug, the sealing of the tongue when formed in the bottom being similar to that in connection with the plug.

I claim:

The combination with a container formed with a delivery opening and a friction cap to seal said opening and capable of removal and replacement for delivery of the contents of the container as desired, of means whereby the cap may be utilized without removal from the container to permit the introduction into the container of coins or the like, said means consisting in dividing the bottom of the cap on three angularly related lines to form a section divided from the cap on three edges with the fourth edge forming a hinge for such section, and a flexible sealing strip to be secured to the bottom of the cap to overlie and seal the lines of division while the section is in the plane of the bottom, said sealing strip being broken on depression of such section to provide an opening in the bottom of the cap.

In testimony whereof I affix my signature.

FRANK E. LOWENSTEIN.
